DRUM

William F. Ludwig, Oak Park, Ill., assignor to
 C. G. Conn, Ltd., Elkhart, Ind., a corporation
 of Indiana

Application May 2, 1936, Serial No. 77,479

8 Claims. (Cl. 84—411)

My invention relates to drums, and especially to drum head tensioning devices.

An object of the invention is to provide a drum head tensioning device wherein the tension rods, 5 or screws, are universally mounted within a casing and connected with a pair of spring pressed nuts.

Another object of the invention is to provide an improved drum head tensioning device in which 10 the parts are wholly concealed within a casing connected with the drum shell.

Other and more specific objects of the invention are mentioned and described herein.

The invention is illustrated in the accompanying drawing, wherein

Figure 1 is a fragmentary elevation of a drum showing one drum head tensioning device only in which my invention is embodied, attached to a drum fragment;

Figure 2 is a bottom plan view of the complete drum head tensioning device only;

Figure 3 is a section taken on line 3—3 of Figure 2; and

Figure 4 is a perspective of one of the tension 25 screw nuts.

Similar numerals of reference indicate like parts throughout the several views on the drawing.

Referring to the details of the drawing, the 30 numeral 1 indicates a fragment of a cylindrical drum shell which may be built in any suitable manner, well known in the art. Numeral 2 indicates the usual skin drum head which may be secured to the hoops 3 in any suitable manner, 35 said hoops being arranged about the ends of the drum shell 1. The usual pair of counter hoops, or rings, 4 are arranged to overhang the hoops 3, as is well known in this art, each of said counter hoops carrying a plurality of apertured brackets, or lugs, 5, also well known, in which the outer ends of the polygonal headed tension screws, or rods, 6 are mounted, traversing the apertures 7 therein.

The tensioning screws 6 extend to the interior 45 of and are adjustably anchored within a casing 8, as herein described, the latter, as illustrated, being preferably a casting made of relatively light weight metal. The casing 8 may be formed with a top wall 9, opposed side walls 10 and 11, and 50 the two end walls 12 and 13, also the two spaced interior transverse walls, or partitions, 14 and 15, whereby end compartments 16 and 17 and a medial compartment 18 are provided within said casing. The end walls 12 and 13 of the casing 55 8 are apertured at 19 and 20, respectively, and

the interior partitions, or walls, 14 and 15 are apertured at 21 and 22, respectively, the latter mentioned apertures aligning with said end wall apertures.

The partition apertures 21 and 22 carry therein the polygonal headed nuts 23 and 24 loosely, or universally, mounted therein, and the tensioning screws 6 extend through the casing end wall openings 19 and 20 and are threaded into and through said nuts and into the medial compartment 18 of the casing. The nuts 23 and 24 are held against rotation by the polygonal head which engages one of the casing side walls 10 and 11. The end wall openings 19 and 20 are made large enough to permit of universal movement of the 15 screws 6 therein, and the inner ends of said screws, which are arranged within the compartment 18, are encompassed by the coil compression spring 25 which seats against a cylindrical reduced portion on the nuts 23 and 24. The 20 function of the spring 25 is to hold the nuts within their sockets 21 and 22 even though the screws 6 may be removed therefrom, thereby facilitating the assembly of said screws with said nuts.

The casing 8 may be fastened to the drum shell 1 by a pair of headed screws 26 and 27 which are threaded into the casing partitions 14 and 15 through suitable apertures in the shell wall. It will be evident from the foregoing that the casing 8 presents an artistic exterior appearance and is wholly free from conditions which might injure the hands or garments of the operator, for the threads of the screws 6 and the nuts 23 and 24 are wholly concealed within said casing.

I claim:

1. A tensioning device for drums comprising, in combination, a casing for attachment to the drum shell, said casing being provided with apertured end walls and a pair of apertured partitions disposed interiorly of the casing, a non-rotatable nut arranged in the aperture of each interior partition of said casing, and two screws cooperating with said two nuts and extending through the casing end wall apertures and 40 adapted to cooperate with the counter hoops of the drum.

2. A tensioning device for drums comprising, in combination, a casing for attachment to the drum shell, said casing being provided with apertured 50 end walls and a pair of apertured partitions disposed interiorly of the casing, a non rotatable nut universally mounted in each interior partition aperture, and two screws cooperating with said two nuts and extending through and uni- 55

versally arranged within said casing end wall apertures, and adapted to cooperate with the drum counter hoops.

3. A tensioning device for drums comprising, 5 in combination, a casing for attachment to the drum shell, said casing being provided with apertured end walls and a pair of apertured partitions disposed interiorly of the casing, a pair of spring pressed non rotatable nuts arranged in the casing partition apertures, and two screws cooperating with said two nuts and extending through the casing end wall apertures and adapted to cooperate with the drum counter hoops.

4. A tensioning device for drums comprising, 15 in combination, a casing for attachment to the drum shell, said casing being provided with two end compartments and a medial compartment, said compartments providing a pair of interior transverse apertured partitions, a non rotatable 20 nut mounted in each transverse partition aperture, and two screws cooperating with said two nuts and extending through said casing end compartments into the casing medial compartment and adapted to cooperate with the drum counter 25 hoops.

5. A tensioning device for drums comprising, in combination, a casing for attachment to the drum shell, said casing being provided with two end compartments and a medial compartment, 30 said compartments providing a pair of transverse apertured partitions disposed interiorly of the casing, a non rotatable nut universally mounted in each partition aperture, means for retaining said nuts in juxtaposition, and two 35 screws cooperating with said nuts and extending through said casing end compartments into the medial compartment thereof and adapted to cooperate with the drum counter hoops.

6. A tensioning device for drums comprising, in combination, a casing for attachment to the drum shell, said casing being provided with two end compartments and a medial compartment, said compartments providing a pair of transverse 5 apertured partitions, a non rotatable nut universally mounted in each transverse partition aperture, spring means for retaining said nuts in juxtaposition, and two screws cooperating with said nuts and extending through said casing end 10 compartments into the medial compartment thereof and adapted to cooperate with the drum counter hoops.

7. A tensioning device for drums comprising a casing for attachment to the drum shell, said 15 casing being provided with a pair of interior apertured nut abutments disposed intermediate the casing extremities, a non rotatable nut universally mounted in each of said nut abutment apertures, two screws cooperating with said two 20 nuts, said screws extending to the exterior of said casing and adapted to cooperate with the drum counter hoops, and spring means for retaining said nuts in said abutment apertures.

8. A tensioning device for drums comprising a casing for attachment to the drum shell, said casing being provided with a pair of apertured nut abutments disposed interiorly of the casing, extending transversely thereof and positioned intermediate the casing extremities, a non rotatable nut universally mounted in each of said nut abutment apertures, and two screws cooperating with said two nuts, said screws extending to the exterior of said casing and adapted to cooperate 25 with the drum counter hoops. 30

WILLIAM F. LUDWIG.
